VENTILATING FAN MOUNTING STRUCTURE

Verner E. Sprouse and Trueman P. Jordan, Columbus, Ind., assignors to V. E. Sprouse Company, Inc., Columbus, Ind., a corporation of Indiana

Application December 20, 1949, Serial No. 134,054

3 Claims. (Cl. 230—117)

1

This invention relates to a ventilating fan of a type normally employed in dwelling houses where quietness of operation is very essential. A common use of the invention is to move air out of a dwelling in order that cool air from the outside, or at least fresh air from the outside may be pulled in to replace that air withdrawn and forced out of the dwelling by the fan construction herein to be considered. While it is highly desirable to have a high efficiency in respect to the ratio of air moved to the power input, as indicated, quietness of operation is of prime consideration.

It is a primary purpose of the invention to provide a mounting structure, self-contained, which will prevent vibrations from any of the moving parts such as the driving motor and the revolving fan from being transmitted to the building structure and to the air itself in the sense that noise will be audible to the inhabitants of the building. Furthermore it is the purpose of the invention to prevent vibrations being set up of such a nature that they will be felt even though not audible. A further primary object of the invention is to provide a structure of the nature indicated wherein those objects will be accomplished even though the mounting structure is made out of much lighter metal than has heretofore been considered possible for the purpose. In other words the invention permits use of less weight of metal while accomplishing that highly desirable end result of no vibration being transmitted either to the air or to the supporting building structure.

These and many other objects and advantages of the invention such as will be found in the peculiar arrangement and assembly of the various elements to facilitate production and assembly, will become apparent to those versed in the art in the following description of one particular form of the invention as illustrated in the accompanying drawings, in which:

Fig. 1 is a view in rear elevation of a structure incorporating the invention;

Fig. 2 is a detail on an enlarged scale in elevation and partial section of the mounting relationship between the fan supporting member and the mounting frame;

Fig. 3 is a vertical transverse section on the line 3—3 in Fig. 1;

Fig. 4 is an inside elevational view of the detail illustrated in Fig. 2; and

Fig. 5, a transverse section on the line 5—5 in Fig. 4.

Referring to the drawings, in which like char-

2

acters of reference indicate like parts, there is formed a mounting frame generally designated by the numeral 10. This frame 10 is generally box-like in nature and is composed of a top, flat metal sheet wall 11, the two vertically disposed, flat metal sheet walls 12 and 13; and the flat, metal sheet floor 14. These bounding walls 11—14 are provided with the outturned flanges 15 and 16 respectively extending entirely therearound to serve as stiffening means. In order to retain these walls in their general rectilinear shape, there are employed the angle plates 17, one across each outer corner on the rear side of the structure, these plates 17 being secured to the flange 15. That side of the structure from which the flange 16 extends will be hereinafter designated as the discharge side, while the side from which the flange 15 extends will be designated as the intake side.

A baffle member 18 is fitted within the four walls and spaced backwardly from the discharge end of the structure a distance approximately one-fourth of the fore and aft length of these bounding walls. This baffle member 18 has a peculiar shape in that it has a foot 19 extending in intimate contact across the inside face of each of the walls 11—14 inclusive. From the foot 19, the member 18 is turned inwardly by a leg 20, Fig. 3, herein shown as being disposed at right angles to the various walls. From the inner portion of the leg 20, there is turned rearwardly within the box structure 10 a web 21, and from the inner edge portion of this web 21, there is turned at right angles therefrom a flange 22 to terminate by a free edge portion 23.

Spaced apart along each of the walls 11—14 inclusive, are a plurality of resilient, vibration absorbing spacers 25. Each of these spacers 25 carry a pair of cap screws 24 and 24a, axially aligned to have their heads imbedded within the spacers 25 and extending by free ends respectively therefrom, Fig. 5. The bolts 24 extend through the post 19 and walls 11—14 to project exteriorly thereof to receive the securing nuts 24b thereon.

A member 26 herein termed a Venturi plate is defined by a rectangular outer marginal portion from which there is turned rearwardly a mounting flange 27. The vertical and transverse dimensions of the outer marginal surface of the flange 27 exceed the corresponding dimensions of the opening in the member 18 as defined by the margin 23 thereof. The plate 26 is provided with a major centrally disposed airflow opening 28. From the margin of this opening 28, there is

extended forwardly toward the discharge side of the frame 10 a tubular neck 29, the diameter of the tubular portion being smaller than the diameter of the opening 28. That is, the tubular portion 29 merges into the plate 26, by a radial portion 30. The forward edge of the tubular portion 29 terminates just inside of the discharge side of the frame 10, Fig. 3.

The flange 27 of the plate 26 is provided with slots 31 spaced apart distances equal to the spacings of the bolts 24a. Each of these slots 31 enters from the rear, free edge of the flange 27 and has its outer portions entering between tongues 32 and 33 constituting portions of the flange 27 turned substantially normal to the flange faces, Figs. 2, 4, and 5.

A pair of fan supporting arms 35 and 36 are secured to the rear side of the plate 26.

As viewed in Fig. 1, the arm 35 has its upper end portion 37 fixed to the plate 26 toward its upper left-hand corner, to extend rearwardly therefrom substantially at right angles to the plate 26. The arm 35 is bent from the straight portion 38 around downwardly and diagonally through the length 39 toward the central portion of the frame 10, and thence is carried downwardly through a vertical disposed portion 40, from which the arm is carried through a diagonally disposed portion 41 and around through a horizontally disposed length 42 to have its end 43 abut the plate 26 and be fixed thereto. In like manner, the arm 36 is fixed to the plate 26 having its upper end portion 44 fixed toward the upper right-hand corner thereof, to extend diagonally downwardly to a centrally disposed vertical portion 45, and thence diagonally outwardly and back to the plate 26 to have its lower end 46 fixed thereto. The centrally disposed, vertical portions 40 and 45 are spaced apart symmetrically from a vertical plane through the axis of the hole 28.

Fixed to these vertical portions 40 and 45 of the arms 35 and 36 respectively is a fan shaft bearing housing 47. The exact configuration and construction of this housing 47 is immaterial to the present invention, but it is essential that it be fixed rigidly and permanently to the arms 35 and 36. Within the housing 47 are carried in spaced apart relation the front and rear fan shaft bearings 48 and 49 respectively.

A fan shaft 50 is revolvably carried by these bearings 48 and 49 and held against longitudinal displacement. On the forward end of the shaft 50 is mounted a fan 51 herein shown as consisting of four blades. The outer portions of the fan blades 51 extend forwardly within the tubular portion 29 of the Venturi plate 26, Fig. 3, and their outer peripheral portions have a slight clearance between them and this portion 29, Figs. 1 and 3.

On the rear end portion of the shaft 50 is mounted a belt pulley 61 around which is carried a driving belt 52, to, in turn, pass around a driving pulley 53 driven by the electric motor 54.

Reverting to the plate 26, this plate is mounted and carried by the mounting frame 10 by having its flange 27 forced rearwardly over the inner ends of the resilient spacers 25, to have the bolts 24a relatively enter the slots 31 in each instance. The flange 27 is then secured against fore and aft displacement by means of nuts 55 screw-threadedly engaged over the inner ends of the bolts 24a and compressibly urging washers 56 against the face of the flange 27 in each instance. The washer 56 is of that diameter which will per-

mit it to lie ahead of the inturned tongues 32 and 33 so that the flange 27 will then be effectively held not only against rearward displacement, but also against forward displacement.

The motor 54 is carried by the plate 26 through a plate 57 which has its forward edge portion resting on top of the flange 27 and extending rearwardly a distance and thence upwardly along the portion 41 of the arm 35, Fig. 1. The plate 57 is secured to that portion 41 in any suitable manner, such as by welding. Preferably a rear resilient cushion 58, Fig. 3, is inserted between the plate 57 and the wall 14 and secured in place by the bolt 59. However, as above indicated, the fan and its driving motor are all carried as an integral unit assembly with the plate 26, all without metallic contact with any of the walls 11-14.

The flange 27 encircling the plate 26 is necessarily spaced from the inner sides of the various walls 11-14 in order to permit that flange 27 to bear against the elastic sleeves 25 in each instance. This means that there might be the chance of air being drawn rearwardly through the front discharge side of the frame 10 back between the flange 27 and the various walls 11-14 if no means were presented to prevent that flow. The function of the member 18 is not only to stiffen the walls 11-14, but to obstruct that possible flow by means of the inwardly extending leg 20 and the web 21 which carries the flange 22 to terminate by the edge 23 spaced inwardly from those walls a greater distance than is the flange 27. Therefore any back flow tendency of the air is resisted by reason of the fact that such flow would have to be in a tortuous manner in order to get back into the housing 10 behind the plate 26.

While reference to the spacers 25 has been made as designating them to be made out of a resilient material, it is implied thereby that they be not only resilient but elastic so that they will tend to hold their original pressed length between the walls 11-14 and the flange 27, and absorb vibrations of the assembly carried by the plate 26 without transmitting those vibrations to the walls 11-14. A suitable material for these sleeves would be rubber either in its natural state or any of the synthetic rubbers of sufficient elastic nature.

While we have herein shown and described our invention in the one particular form as now best known to us, it is obvious that structural variations may be employed without departing from the spirit of the invention, and we therefore do not desire to be limited to that precise form beyond the limitations which may be imposed by the following claims.

We claim:

1. A fan mounting structure comprising a box; a Venturi-plate member; a pair of arms, each having ends secured to a common side of said member, and the major portions of the arms spaced from the member and from each other; a fan shaft; fan shaft support means fixed to said arms to carry the shaft axially of said member; said Venturi-plate member having a central air flow opening therethrough, the marginal plate portion defining said opening being extended in a reduced diameter neck portion; a fan mounted on said shaft to extend by its discharge side into said neck portion; said Venturi-plate member having an outer edge contour defining an area less in extent than the cross-sectional area of said box; a plurality of elastic spacing members

mounted around the inside of said box; said Venturi-plate member having its said outer edge seated on said spacing members whereby said Venturi-plate member is spaced from contact with said box; means securing said Venturi-plate member in position on said spacing members; and a fan drive motor carried by said plate member; and a baffle member interengaged between said spacing members and said box and having a flange portion extending centrally inwardly from the box a distance further than said plate member edge portion and spaced longitudinally therefrom in respect to axial direction of said shaft.

2. A fan mounting structure comprising a box; a plate member having a Venturi orifice therethrough and positioned to extend across the box; a plurality of vibration absorbing spacers between the marginal edge portion of the plate member and said box to provide a resilient mounting of the plate member in spaced relation from the box; a fan revolvably carried by said plate member to have its discharge side located to carry air through said orifice; and a fan drive motor also carried by said plate member; and a baffle member spaced from said plate member to extend inwardly of the box a distance exceeding the spacing of the plate member therefrom.

3. A fan structure comprising a box; a Venturi-plate; a peripheral flange around the plate and extending normally therefrom, said flange having spaced apart slots entering from the edge thereof; tongues turned inwardly from the margins of said slots, the bend lines of the tongues at the flange being diagonally disposed outwardly of the flange, one line diverging from the other at each slot entrance; said plate having less overall dimensions than the corresponding dimensions

of the box whereby the plate is received within the box to extend thereacross to have said flange spaced entirely therearound from the box; vibration absorbing spacers between said box and said flange, one of said spacers being located at each of said flange slots; bolts located in the box, one each to carry one of said spacers; a bolt carried by each spacer to be entered in the corresponding flange slot; a nut screw-threadedly engaging each bolt over said flange between the plate and said tongues to restrain the plate against travel through the box; a fan mounted on said plate to carry air through said plate; and a motor carried by the plate to drive the fan; whereby said plate, fan, and motor form an assembly insulated from the box to eliminate substantially transmission of vibration to the box; and a baffle ring secured to said box to extend across the clearance space between said plate flange and the box, the ring having a portion thereof spaced from the plate along said box.
